UNITED STATES PATENT OFFICE.

EMIL MERTZ, OF TYGH VALLEY, OREGON.

FOLDING CRATE.

1,352,299.

Specification of Letters Patent.

Patented Sept. 7, 1920.

Application filed February 3, 1920. Serial No. 356,012.

To all whom it may concern:

Be it known that I, EMIL MERTZ, a citizen of the United States, residing at Tygh Valley, in the county of Wasco and State 5 of Oregon, have invented new and useful Improvements in Folding Crates, of which the following is a specification.

This invention relates to shipping crates, particularly to crates adapted for the shipment of poultry, and has for its object the provision of a crate in which the sides and ends are foldable to lie between the top and bottom so that the device will occupy but little space in transportation or storage and 15 will therefore be inexpensive to ship in knock-down condition.

An important object is the provision of a crate of this character in which means are provided for securing the top and bottom 20 together when the crate is in either set-up or collapsed condition.

An additional object is the provision of a folding crate of this character which will be comparatively simple and inexpensive in 25 manufacture, highly efficient in use, economical in service, durable, and a general improvement in the art.

With the above and other objects and advantages in view the invention consists in 30 the details of construction to be hereinafter more fully described and claimed, and illustrated in the accompanying drawings in which—

Figure 1 is a side elevation of the crate in 35 set-up position,

Fig. 2 is an end elevation,

Fig. 3 is a cross sectional view,

Fig. 4 is a detail view showing the locking means,

Fig. 5 is a side elevation with the crate in folded position,

Fig. 6 is a cross sectional view there- 40 through, and

Fig. 7 is a plan view of the bottom show- 45 ing the corner members engaged in the clips thereon.

Referring more particularly to the drawings, the numeral 10 designates the bottom of the crate which may be formed of metal 50 or of any suitable number of boards or the like, properly secured together. Secured at the sides of the bottom upon the top thereof, are longitudinally extending bars 11. Hinged upon the end portions of the bottom 55 upon the top side thereof, are the ends 12 which are adapted to lie flat upon the bot-

tom when the crate is collapsed and which are then adapted to be flush with the top of one of the bars 11. Hingedly connected with the bars 11 are the sides 13, one of 60 which is adapted to be folded flat upon the folded ends and the other of which is adapted to be folded flat upon the first folded side, it being noticed that one of the bars 11 is of greater height than the other where- 65 bv to permit this action.

In order that the sides and ends may be secured in set-up position, I provide plates 70 14 which are secured upon the top of the bottom at the corners thereof adjacent the bars 11 and these plates are provided with threaded holes 15. Secured upon the sides of the ends 12 are loops 16 and secured upon the ends of the sides 13 are similar loops 17 adapted to register with the loops 16 when 75 the sides and ends are in set-up position. I further provide bolts 18 which are extended through the registering loops 16 and 17 and which are then threaded into the holes 15 in the plates 14. These bolts have their 80 heads designated by the numeral 19.

The top of the crate is designated by the numeral 20 and may be of any suitable construction, either metal, wood, or screen, and this top is of the same size and shape as 85 the bottom 10. The top is designed to fit flat upon the upper edges of the sides and ends, all of these edges being flush and this top is provided with holes 21 at its corners, through which the heads 19 of the bolts are 90 adapted to extend.

In order to hold the top in assembled position, I provide latch members 22 pivoted upon the top adjacent each hole therein and these latch members are in the nature 95 of hooks adapted to engage beneath the heads of the bolts. It is believed from the above description, that the construction of the crate and its setting up will be thoroughly understood without further elabora- 100 tion.

When it is desired to collapse the crate, it is first necessary to swing the loop members 22 out of engagement with the bolts 18, unscrew the bolts 18 from the plates 14, 105 remove the bolts, and then swing the ends onto the bottom and then swing one side onto the folded ends, and then the other side onto the first named side. It will be observed that I make use of clips 23 secured 110 upon the top of the bottom within which the bolts may be engaged prior to the swing-

ing in of the sides and ends. After the ends and sides have been thus collapsed the top is inverted and superposed thereon, that is laid upon the uppermost side.

5 The top is then held upon the folded body of the crate by means of hooks 24 which are or may not be spring hooks, as preferred, which are secured to the bars 11, and which are engageable within screw eyes 25 carried by the top. When the crate is thus collapsed and secured it will be seen that it will occupy but small space during storage or transportation and will therefore be economical in shipment.

10 15 While I have described the device throughout as a crate, it is of course to be readily understood that it may be formed of slatted material and be thus adapted for use as a coop for the shipment of poultry or the like. It will also be observed that it may be formed of wood, metal, or screen and it is to be understood that I reserve the right to make any other such changes as fall within the scope of the following claims.

15 20 25 Having thus described my invention, I claim:

1. A folding crate comprising a bottom, sides and ends hinged upon the bottom, loops carried by the ends of the sides and ends and adapted to be brought into registration, corner bolts passing through the registering loops and threaded into the bottom, a top engaged upon the heads of the

bolts and prevented thereby from longitudinal or lateral displacements, and means 35 carried by the top and engaging said bolts for holding said top against movement away from the bottom.

2. A folding crate comprising a bottom, sides and ends hinged thereon, loops carried by the sides and ends and adapted to be brought into registration, bolts passing through said registering loops and engaging the bottom and having angular heads, a top resting upon the upper edges of the sides and ends and having holes through which the heads of the bolts pass, and members carried by the top and detachably engaging beneath the heads whereby to hold the top against movement away from the bottom. 40 45 50

3. A folding crate comprising a bottom, sides and ends hinged thereon, loops carried by the sides and ends and adapted to be brought into registration, bolts passing through said loops and engaging the bottom, a top seating upon the upper edges of the sides and ends and having holes through which the heads of the bolts pass, and pivoted arms carried upon the top and formed with notches engageable upon said bolts beneath the heads thereof whereby to hold the top against movement away from the bottom. 55 60 65

In testimony whereof I affix my signature.

EMIL MERTZ.
